UNITED STATES PATENT OFFICE

2,010,622

HOUSING HEATER

Ray A. Brown, Rockford, Ill.

Application March 20, 1933, Serial No. 661,808

20 Claims. (Cl. 219—47)

This invention relates to a heater for heating housings on motor vehicles principally with a view to facilitating servicing.

The present practice in cleaning out differential and transmission housings for replacing the lubricant is to use steam to loosen and clear out the lubricant, or to flush out the same with kerosene or gasoline. Both methods have serious objections. It is, therefore, the principal object 10 of my invention to provide a portable heater for application to the housing to render the lubricant sufficiently fluid by heating to permit easy drainage. An important feature of this heater is that it heats by the passage of magnetic flux back and forth through the housing wall, the heater being of an electromagnetic type operated preferably on alternating current, or on direct current using an interrupter.

Another object of the invention is to provide 20 a heater of the kind mentioned constructed to promote convenience in application to the housing to be heated, and so as to adapt the heater to use on different sizes and shapes of housings.

Other objects and advantages of my invention 25 will appear in the course of the following detailed description, in which reference is made to the accompanying drawings, wherein—

Figure 1 is a rear view of an automobile showing the heater of my invention in position on the differential housing;

Fig. 2 is a view of the housing and heater on a larger scale showing the heater in vertical cross-section;

Fig. 3 is a side view of the heater;

Fig. 4 is a view similar to Fig. 2 but showing a heater of modified or alternative construction having adjustable jaws to accommodate a large range of housings of different sizes and shapes;

Fig. 5 is a side view of the heater illustrating 40 how the jaws are adapted to conform themselves to the contour of the housing;

Fig. 6 is another view similar to Figs. 2 and 4 but showing a still further modified or alternative construction;

Fig. 7 is a side view of the lower portion of the heater with a portion broken away to permit showing the parts on a larger scale;

Fig. 8 is a cross-section of Fig. 7, and

Fig. 9 is a horizontal section on the line 9—9 of Fig. 8.

Similar reference numerals are applied to corresponding parts throughout the views.

In Figure 1 the heater of my invention is indicated generally by the numeral 10 in position on the differential housing 11 of an automobile for

the purpose of making the lubricant therein sufficiently fluid by heating the wall of the housing, to permit easy drainage when the plug is removed. In other words, nothing foreign is allowed to get into the housing and interfere with good lubrication. Where steam was used, there was always some water left in the housing which in cold weather would freeze, and in any event, was objectionable for obvious reasons. Where kerosene or gasoline was used it got into 10 the working parts and kept lubricant from getting in so that the parts were improperly lubricated. The kerosene or gasoline also caused objectionable dilution of the lubricant. Aside from the fact that the steam, kerosene or gasoline 15 left the housing in an unfit condition, the use of such a medium was objectionable because of the amount of time consumed; the heater of my invention performs the operation in a fraction of the time. While I have shown the heater applied to a differential housing, it should be understood that it may also be applied to the transmission housing for a similar purpose or to the engine crank case either for the same purpose, or for the purpose of preparing a frozen up car 20 for starting. Heaters of this type will find use at air ports for heating the crank cases of air-craft engines in preparation for flight, thereby reducing the fuel consumption and time loss in warming up. It will further appear that while 25 I have shown an automobile, the invention is applicable to any motor vehicle.

The heater 10 is of an electromagnetic type connected by means of a suitable extension cord 13 with an electric light socket in an A. C. or D. C. 35 line with a view to heating the wall of the housing by the passage of magnetic flux back and forth through the wall. In a D. C. circuit it is apparent that an interrupter has to be used in order to secure reversal of the flux, or simply intermittent flux. At present, I prefer the use of alternating current because it avoids any condition of residual magnetism in the part heated and seems to heat more efficiently. Reversal of direct current would, of course, give the same advantage. 40 Experiment has shown that it takes but a few minutes to heat a cold housing sufficiently to render the lubricant therein fluid so that it may be drained out easily. The heater, as best appears in Fig. 2, has a laminated core 14, the pieces of 45 which are placed at right angles to each other and suitably riveted together, as indicated at 15, the outer ends of the pieces having right angle portions 16 riveted together as at 17 and forming the jaws for application to the wall of the

housing. In Fig. 2 I have indicated flux lines to give a better idea of the way in which the heater works. Two coils are indicated at 18 on the two legs of the core 14. These are suitably connected together either in series or parallel, and, of course, have connection with the wires of the extension cord 13. The housing 19 of the heater is of non-magnetic material and made in two pieces, as appears in Fig. 3 so as to permit assembling on the heater from opposite sides. Any suitable means may be employed for fastening the housing sections together. Hooks 20 are formed on the housing sections to permit suspension of the heater on the rear axle by chains or cables, as indicated at 21. When the heater is brought into place from a pit or where the differential housing is high enough to permit, blocks or a jack may be provided to support the heater with or without the chain or cable. In that event, the flat surface 22 on the bottom of the heater is used for engagement of the blocks or jack. The plunger of a jack is indicated in dotted lines in Fig. 2 in engagement with the surface 22. Any pressure exerted on the surface 22 is transmitted directly to the core 14 because of the fact that the crotch of the core fits into a right angle pocket 23 in the bottom of the housing. There is, therefore, no danger of distortion if more than the necessary pressure is brought to bear. Sufficient space is left in the housing 19 between the coils 18 and alongside the core 14 to permit mounting a switch 24 directly on one of the housing sections. See Fig. 3. The lever 25 of the switch 24 projects from the housing for convenient operation, and has a projection 26 alongside the same to serve as a guard to prevent damage to the switch and accidental opening or closing of the circuit by something coming in contact with the switch lever. When a heater of the present construction is so designed to bring the jaws 16 near the axle bearings at the ends of the housing 11, heat will be transmitted along the axle sections to the differential gearing so that the lubricant thereon will become fluid and drain off. However, it may be found desirable to provide a heater with adjustable jaws to permit placing them in the most advantageous position on different sizes and shapes of housings. A heater of such construction is shown in Fig. 6, to which attention is now directed.

The heater 10-a has the laminated core thereof made in two sections, 14-a and 14-b hingedly connected together so as to permit adjusting the jaws 16-a for contact with the ends of a housing regardless of the particular size or shape. This construction also will facilitate application of the heater to transmission housings and crank cases. Due to the fact that the heater consists of hinged sections, separate housings 19-a and 19-b are provided for the coils on the core connected with the extension cord 13. The core sections 14-a and 14-b extend from the lower end of the housings as shown, and have through bolts 36 and 37 extended therethrough to provide pivots as well as clamping means. Links 38 interconnect the bolts at the front and back and are received between the arms 39 of a yoke 40, through which the bolt 36 extends, as indicated in Figs. 7 and 9. By providing two pivots at 36 and 37 I am enabled to get away from the condition illustrated in Fig. 5 on heater 10'; both sections of the core can be made solid without any air spaces between laminae. As shown in Fig. 8, the pieces of the one core section have the lower ends cut on an arc 44 with the bolt 37 as a

center, and the mating pieces on the other core section have their lower ends cut out on a corresponding arc 42, to permit the angular adjustment of the section 14-b about the bolt 37 as a center so as to widen or shorten the distance between the jaws 16-a. When the core has been adjusted as desired, the wing nuts 41 on the bolts 36 and 37 can be tightened to clamp the parts rigidly in adjusted position. The bottom of the yoke 40 provides a place for engaging a jack or block to support the heater. Hooks 20 can be provided for suspension of the heater on the housing. The heater 10' shown in Fig. 4 is another one having adjustable jaws, and attention is now directed to Figs. 4 and 5.

The heater 10' has a laminated core 14', the pieces of which are made to extend the full length of the housing 19' and to project from opposite ends thereof for attachment thereto of jointed adjustable jaws 16'. The jaws 16' are formed in two laminated sections 27 and 28, the former pivoted to the ends of the core 14', as indicated at 29, and the other section pivoted to the end of the first section, as indicated at 30. Through bolts are provided for the pivots having heads on one end and wing nuts 31 on the other end to permit clamping the sections in adjusted positions. Suitable bands 32 are provided to hold the pieces of section 28 bunched. It is manifest that with jaws of such construction one may place the same in various positions according to the size and shape of housing to be heated, and there is no difficulty in bringing the jaws into contact with the housing at or near the bearings at the ends of the housing to accomplish the result previously referred to. This construction furthermore involves the provision of slots 33 on the pieces of the jaw section 28 to permit the pieces to slide endwise with respect to one another and relative to the bolt 30 to arrange the ends in an arc or otherwise in order to engage quite a large area on the surface of the housing, regardless of its curvature or other peculiar shape. See Fig. 5. The nuts 31 on the bolts 30 would, of course, have to be loosened sufficiently to permit sliding of the pieces in the manner stated, and once the pieces were arranged as desired, the nuts could be retightened.

In order to relieve the jointed jaws 16' of pressure that might be sufficient to force them out of position, I have provided a middle projection 34 on each of the pieces of the core 14' for engagement with the bottom of the housing. The sections of the housing 19' of the heater are formed as appears at 35 to have abutment with the core at the middle so as to transmit pressure directly to the core at the proper point when a jack or blocks are engaged on the flat surface 22' in holding the heater in place under the housing to be heated. Another advantage flowing from the provision of a middle pole is that the path of the magnetic flux is shortened proportionately and the operation of the heater is made more efficient. In this heater, as in the other, it is also contemplated to provide hooks 20 to permit suspension of the heater on the rear axle housing. The housing 19' in this case as in the other is preferably of two-piece construction to make for cheapness and ease in assembling.

In operation, it will be apparent that the use of chains or cables for suspension of the heater from the housing, or the use of a jack or blocks to support the heater under the housing is in reality required only up to the time that the switch 24 is closed and the coils 18 energized; 75

from that time on, up to the time the circuit is broken again, the heater is supported by magnetic attraction. It is not necessary, therefore, to do anything more than bring the jaws 16 or 16' into contact with the housing at the outset, because these jaws will be drawn into firm contact with the housing just as soon as the current is turned on.

The present device, in addition to being useful in draining lubricant from housings, is also useful as a good means of checking the amount of lubricant present in a housing, because it can be applied to the housing long enough to drain all of the lubricant to the bottom, and then, when the plug at the sight opening, usually provided for the purpose of checking the level of lubricant, is removed, one can tell immediately whether there is sufficient lubricant or whether some should be added to bring the level up to the opening. In that way there is a saving in expense to the motorist because he saves the cost of what surplus lubricant might be put in and any repair bills that might arise from surplus lubricant working its way out of the housing, and, on the other hand, he saves repair bills due to not having sufficient lubricant.

It is believed the foregoing description conveys a good understanding of the objects and advantages of my invention. The following claims have been drawn so as to cover all legitimate modifications and adaptations.

I claim:

1. A heater for application to a motor vehicle differential or transmission housing to be heated comprising contact jaws for engagement with the housing at spaced points, and means for inducing electromagnetic flux passage of some frequency and alternating direction through the wall of said housing from one of the jaws to the other, whereby to heat the housing.

2. A heater for application to a motor vehicle differential or transmission housing to be heated comprising contact jaws for engagement with the housing at spaced points, a core of magnetic material completing a magnetic circuit between said contact jaws, whereby to permit the passage of magnetic flux of some frequency and alternating direction through the wall of said housing between the points of contact of the jaws therewith to heat the same, and means for inducing the passage of magnetic flux of some frequency and alternating direction in the circuit.

3. In combination, a rear axle differential housing having differential gearing therein and axle sections connected with the gearing and received in bearings at opposite ends of the housing, a heater for heating the housing and gearing therein comprising contact jaws for engagement with the housing at opposite ends in the vicinity of the bearings, and means for inducing electromagnetic flux passage of some frequency and alternating direction through the wall of said housing from one of the jaws to the other, whereby to heat the housing and transmit heat through the bearings and axle sections to the differential gearing.

4. In combination, a rear axle differential housing having differential gearing therein and axle sections connected with the gearing and received in bearings at opposite ends of the housing, a heater for heating the housing and gearing therein comprising contact jaws for engagement with the housing at opposite ends in the vicinity of the bearings, a core of magnetic material completing a magnetic circuit between said

contact jaws, whereby to permit the passage of magnetic flux of some frequency and alternating direction through the wall of said housing between the points of contact of the jaws therewith to heat the same and transmit heat through the bearings and axle sections to the differential gearing, and means for inducing the passage of magnetic flux of some frequency and alternating direction in the circuit.

5. In combination, a rear axle differential housing having differential gearing therein and axle sections connected with the gearing and received in bearings at opposite ends of the housing, a heater for heating the housing and gearing therein comprising means for applying heat to the housing in the vicinity of said bearings, whereby to heat the housing and at the same time transmit heat through the bearings and axle sections to the differential gearing.

6. As a means for heating an object of magnetic material, contact jaws for engagement with the object at spaced points, and means for inducing electromagnetic flux passage of some frequency and alternating direction through the object from one of the jaws to the other, whereby to heat the object.

7. As a means for heating an object of magnetic material, contact jaws for engagement with the object at spaced points, a core of magnetic material completing a magnetic circuit between said contact jaws, whereby to permit the passage of magnetic flux of some frequency and alternating direction through the object between the points of contact of the jaws therewith to heat the same, and means for inducing the passage of magnetic flux of some frequency and alternating direction in the circuit.

8. A portable electric heater of the character described for application to the raised bottom of a device to be heated, comprising an electromagnetic core having object contacting portions to engage the object to be heated at spaced points thereon, one or more coils surrounding the core for induction of electromagnetic flux therein, said coils being arranged to have electric current supplied thereto so as to cause electromagnetic flux passage of some frequency and alternating direction through the core and the object engaged by its contact portions whereby to heat the latter, said core being attracted to the object magnetically during normal operation, whereby the same is self-supporting, and auxiliary supporting means for said device.

9. A portable electric heater of the character described for application to the raised bottom of a device to be heated, comprising an electromagnetic core having object contracting portions to engage the object to be heated at spaced points thereon, one or more coils surrounding the core for induction of electromagnetic flux therein, said coils being arranged to have electric current supplied thereto so as to cause electromagnetic flux passage of some frequency through the core and the object engaged by its contact portions whereby to heat the latter, a housing of suitable material enclosing the core and coils and having provision for supporting the heater by means of the housing, and means in the housing engaging a portion of the core to transmit thrust from the housing to the core and thence to the object engaged by the latter.

10. As a heater, an electromagnet having a plurality of spaced jaws for engagement with a metallic object to be heated and means for inducing electromagnetic flux passage through the

- jaws and object of some frequency and alternating direction, whereby to cause heating of the object.
11. A heater for application to a housing to be heated comprising contact jaws for engagement with the housing at spaced points, and means for inducing electromagnetic flux of a certain frequency through the wall of the housing from one of the jaws to the other, whereby to heat the housing.
12. In combination, a rear axle differential housing having differential gearing therein and axle sections connected with the gearing and received in bearings at opposite ends of the housing, a heater for heating the housing and gearing therein comprising contact jaws for engagement with the housing at opposite ends in the vicinity of the bearings, and means for inducing electromagnetic flux passage of some frequency through the wall of said housing from one of the jaws to the other, whereby to heat the housing and transmit heat through the bearings and axle sections to the differential gearing.
13. As a means for heating an object of magnetic material, contact jaws for engagement with the object at spaced points, and means for inducing electromagnetic flux passage of some frequency through the object from one of the jaws to the other, whereby to heat the object.
14. A portable electric heater of the character described, comprising an electromagnetic core having object contacting portions to engage the object to be heated at spaced points thereon, one or more coils surrounding the core for induction of electromagnetic flux therein, said coils being arranged to have electric current supplied thereto so as to cause electromagnetic flux passage of some frequency through the core and the object engaged by its contact portions whereby to heat the latter, said core being attracted to the object magnetically during normal operation, whereby the same is self-supporting, and auxiliary supporting means for said device.
15. As a heater, an electromagnet having a plurality of spaced jaws for engagement with a metallic object to be heated and means for inducing electromagnetic flux passage through the jaws and object of some frequency, whereby to cause heating of the object.
16. A heater for application to a housing to be heated, comprising a core of magnetic material having contact jaws in magnetic circuit therewith for engagement with the housing at spaced points, said jaws being adjustable relative to one another to vary the spaced relationship, and means for inducing electromagnetic flux passage through the core and jaws and through the wall of said housing whereby to heat the latter.
17. In combination, a rear axle differential housing having differential gearing therein and axle sections connected with the gearing and received in bearings at opposite ends of the housing, and a heater comprising contact jaws adjustable toward and away from one another to permit placing the same in engagement with the housing at opposite ends in the vicinity of the bearings, whereby to heat the housing and at the same time transmit heat through the bearings and axle sections to the differential gearing.
18. In combination, a rear axle differential housing having differential gearing therein and axle sections connected with the gearing and received in bearings at opposite ends of the housing, and a heater comprising a core of magnetic material having contact jaws in magnetic circuit therewith adjustable relative to one another for engagement with the housing at opposite ends thereof, and means for inducing the passage of magnetic flux through the core and jaws whereby to heat the housing.
19. As a means for heating different sized objects of magnetic permeable material, contact jaws for engagement with spaced points of the object to be heated, said jaws being mounted for adjustment toward and away from one another so as to be adapted for application on different sized and different shaped objects, and a core with which said adjustable jaws maintain a closed magnetic circuit in different positions of adjustment, the circuit being closed by the object interposed between the jaws, and said core having electrical means for inducing magnetic flux passage in the circuit for heating the object.
20. A portable heater of the character described comprising contact jaws for engagement with spaced points of a housing of magnetic permeable material, said jaws being mounted for adjustment toward and away from one another so as to be adapted for application on different sized and different shaped housings, and a core with which said adjustable jaws maintain a closed magnetic circuit in different positions of adjustment, the circuit being closed by the housing interposed between the jaws, and said core having electrical means for inducing magnetic flux passage in the circuit for heating the housing.

RAY A. BROWN.
